UNITED STATES PATENT OFFICE.

JAMES H. OSTEN AND ROBERT G. OSTEN, OF PLANO, ILLINOIS.

ROAD-GRADING MACHINE.

1,086,554.

Specification of Letters Patent. Patented Feb. 10, 1914.

Application filed August 22, 1912. Serial No. 716,556.

To all whom it may concern:

Be it known that we, JAMES H. OSTEN and ROBERT G. OSTEN, citizens of the United States, residing at Plano, in the county of Kendall, State of Illinois, have invented a new and useful Road-Grading Machine, of which the following is a specification.

This invention relates to road grading machines, one of its objects being to provide a machine of this character so constructed as to prevent dirt from piling up in front of the scraping blade and interfering with the operation of the machine, it having been found that this objectionable result often occurs in connection with road graders such as heretofore constructed and particularly where soil is gathered up by the scraper.

A further object is to provide an improved connection between the scraping blade and the wheel supported structure whereby said blade can be readily shifted angularly without lost motion and without causing any of the parts to bind to an undesirable extent.

25 A further object is to provide improved means for adjusting the blade angularly and to provide additional means for holding the blade fixed with relation to the main beam subsequent to the adjustment of the blade.

30 A further object is to provide novel means for shifting the beam laterally relative to the rear supporting wheels.

Another object is to provide improved means for raising and lowering the blade quickly.

With the foregoing and other objects in view which will appear as the description proceeds, the invention resides in the combination and arrangement of parts and in 40 the details of construction hereinafter described and claimed, it being understood that changes in the precise embodiment of the invention herein disclosed, can be made within the scope of what is claimed, without departing from the spirit of the invention.

In the accompanying drawing the preferred form of the invention has been shown.

In said drawings Figure 1 is a plan view of the machine. Fig. 2 is a side elevation thereof. Fig. 3 is a vertical longitudinal section through a portion of the machine. Fig. 4 is a perspective view of the draw bar. Fig. 5 is a detail view of the guide bracket used in connection with the half circle. Fig. 55 6 is an enlarged vertical longitudinal section through a portion of the steering mecha-

nism. Fig. 7 is an enlarged view partly in section and partly in elevation showing the means for adjustably connecting one of the gage plates or runners to the scraper blade. 60

Referring to the figures by characters of reference 1 designates the main beam of the machine, the same being channeled longitudinally and provided, between its ends, with an arched portion 2, there being oppositely disposed socket members 3 secured to the bottom face of the beam 1 at the rear end of the arch 2, these socket members being detachably connected by bolts, as shown. 65

A tubular hanger 4 extends downwardly from the front portion of the beam 1 and a vertical shaft 5 is mounted for rotation therein. The hanger 4 is connected to the beam 1 by means of an arm 6 extending rearwardly therefrom as shown and a recess 7 is formed 70 in the upper end of the hanger 4. Secured to the shaft 5 and extending loosely into the recess 7 is a forwardly extending draft plate 8 and another plate 9 is secured to the upper end of the shaft 5 and above the sides of the beam 1, said upper plate 9 being spaced from the bottom of the beam 1 by a spacing sleeve 10 mounted on the shaft 5. The front ends of the two plates 8 and 9 are connected by a bolt 11 and an ear 12 extends upwardly 75 from the top plate 9 and is adapted to be pivotally engaged by a draft tongue 13.

The lower end of the shaft 5 is clamped between opposed members of a depending yoke 14, this yoke having oppositely disposed openings 15 therein for the reception of trunnions 16 extending in opposite directions from the members of a clamp 17. Said clamp is secured upon the middle portion of an axle 18 supported at its ends by 80 front wheels 19. A spacing sleeve 20 is mounted on the shaft 5 between hanger 4 and yoke 14. From the foregoing description it will be apparent that the front axle 18 is free to swing about the trunnions 16 85 100 as an axis and, at the same time, the entire axle can be turned about the axis of the shaft 5, motion being transmitted to said shaft from the draft tongue 13 and the plates 8 and 9 which are fixedly connected to the shaft. 105

By providing a front axle which is free to oscillate in the manner described, it is capable of passing more readily over an uneven surface and without danger of causing the machine to tilt laterally. Furthermore, by mounting the front wheels in the manner described, a very short turn can be 110

made inasmuch as the wheels can pass freely under the front portion of the beam 1.

As shown in the drawings the sides of the channelled beam 1 are formed with openings 21. The socket members 3 receive between them a ball 22 formed at the upper end of a stem 23, this stem being connected to the center of the back face of an elongated scraper blade 24. The front face of this blade is curved downwardly and forwardly to a straight active edge. A half-circle brace 25, preferably formed of an angle strip is secured to the back face of the scraper blade, the ends of said brace being downturned, as at 26 and each of said ends forming one wall of a socket 27. The other walls of these sockets are formed by an angular bracket 28 suitably secured to the back face of the scraper blade 24. A wear strip 29 is secured to the scraper blade 24 and extends along the rear face thereof into the socket 27, said strip 29 being curved so as to constitute an abutment for the purpose hereinafter set forth.

25 A curved draw bar 30 constitutes a connection between the front portion of the beam 1 and either end portion of the scraper blade 24. This draw bar, as shown particularly in Fig. 4, has an eye 31 at its rear end while its other end is provided with oppositely extending curved stems 32, each stem extending laterally and thence upwardly relative to the bar. If the blade 24 is inclined forwardly with its left end in advance of its right end, the draw bar 30 is to be placed at the left side of the beam 1 and the right hand stem 32 of the bar 30 is inserted into one of the openings 21. The rear end portion of the draw bar is then inserted into the socket 27 adjacent the left end of the blade 24 after which a set screw 33, which is carried by the eye 31, is screwed against the curved wear plate 29 so as to bind tightly thereagainst. With the parts 35 thus fitting snugly together it will be seen that the front end of the scraper blade 24 will be securely braced against rearward movement. It will be apparent, of course, that when the right end of the blade 24 is in advance of the left end thereof, the draw bar 30 can be placed at the right side of the beam 1 and the other stem 32 inserted into the beam while the rear end of the draw bar 30 is inserted into the socket 27 adjacent the right end of the blade 24.

Both ends of the blade 24 are provided, on their rear faces, with guide brackets 34. Each of these brackets 34 has a stem 35 mounted to slide and rotate therein, the said stem projecting upwardly from a gage plate or runner 36. A yoke 37 straddles the upper end of the stem 35 and is slotted, as at 38, the said slots receiving trunnions 39 extending radially from the stem 35. A toothed arm 40 is formed integral with the

yoke 37 and extends downwardly therefrom between ears 41. A cam 42 is mounted for rotation between these ears and is adapted to engage arm 40 and clamp certain of the teeth thereof into engagement with teeth 43 formed on the bracket 34 and between the ears 41. A ring 44 is carried by the toothed arm 40 and is adapted to engage the arm of cam 42 so as to hold said cam against rotation while in clamping position. From the foregoing description it will be apparent, that by loosening cam 42, the toothed arm 40 can be shifted out of engagement with the teeth 43 and the stem 35 can thus be adjusted longitudinally within the bracket 34. After such adjustment the arm 40 can be swung into engagement with the teeth 43 and the cam tightened and then held by means of the ring 44. As the stem 35 is mounted for rotation and as it has trunnions 39 projecting into slots 38 in yoke 37, it will be seen that the stem is capable of rotating freely although held against longitudinal movement. This rotation is necessary in order that the gage plate or runner 36 may be held parallel with the path of movement of the machine.

Arranged at each side of the beam 1 are frame members 45, these frame members being pivotally connected, at their front ends, to the beam 1, as by means of a bolt 46. This bolt is preferably located adjacent the front end of the arched portion of the beam 1 and the rear portions of the frame members 45 are preferably curved downwardly, as shown at 47 and provided, at their lower ends, with angular sleeves 48 having rearwardly projecting extensions 49. A bar 50 connects the rear portions of the frame members 45 so as to prevent them from spreading apart. These frame members also support, between them, an elongated U-shaped guide 51 into which the rear end of the beam 1 projects, said beam being adapted to slide vertically within the guide. Suitable braces connect the guide to the frame members 45, certain of these braces being indicated at 52.

Secured to the bottom face of the beam 1 and close to the guide 51 is a bracket 53 having a forwardly extending tongue 54 adapted to project under the half circle 25. The upper face of this tongue is beveled up to a longitudinal ridge 55 constituting a bearing for the lower surface of the half circle or arcuate brace 25. Thus it will be seen that said ridge constitutes a bearing for the half circle and on which the same is free to tilt. An opening 56 is formed in the tongue and registers with a corresponding opening 57 in the beam 1 and the half circle is provided with a series of openings 58 any one of which is adapted to register with the openings 56 and 57 so as to receive a locking pin 59 such as shown in Fig. 3.

A bar 60 extends transversely of and is 130

secured to the frame members 45 and mounted on this bar is a spring 61 one arm of which engages one of the frame members 45 so as to be held against movement while the other arm, indicated at 62, is connected, by a depending link 63, to the rear portion of the beam 1. This spring thus serves to yieldingly support the rear end of the beam and to facilitate the elevation thereof relative to the frame members 45. A rack bar 64 is pivotally connected to and extends upwardly from the rear portion of the beam 1 and slides within a guide 65 supported within the upper portion of the U-shaped guide 51. 10 A shaft 66 is journaled in the guide 65 and has a gear 67 secured to it and meshing with the rack bar 64. A wheel 68 rotates with shaft 66 and is adapted to be rotated by hand, whereby gear 67 is revolved and the rack bar 64 is shifted longitudinally so as to either raise or lower the rear end of the beam 1. Shaft 66 is normally held against rotation by means of a brake lever 68 which is pivotally mounted upon one side of the U-shaped guide 51 and has its forward end connected, by a spring 69, to an ear 70 20 outstanding from the lower portion of the U-shaped guide 51. The rear end of the brake lever 68 is connected by a link 71 to a foot lever 72, said lever being fulcrumed on a bracket 73 upstanding from a platform 74. Said platform is fixedly connected to and extends rearwardly from the frame members 45 and has a standard 75 mounted thereon 25 for carrying the seat 76 to be occupied by the operator. A brake shoe 77 is carried by the brake lever 68 and normally engages the periphery of wheel 68'. The frictional engagement of the shoe with this wheel will of course hold shaft 66 and gear 67 against rotation until the brake lever 68 is shifted away from wheel 68' by means of the foot lever 72.

Brackets or bearings 78 are arranged on the frame members 45 and a shaft 79 is journaled therein and is provided at each end with a crank arm 80. A worm wheel 81 is secured to this shaft and is engaged by a worm 82 formed on or secured to a rearwardly and upwardly extending controlling shaft 83, said shaft being journaled in one of the brackets or bearings 78. A hand wheel 84 is arranged at the rear end of shaft 83 and by means thereof the said shaft and the worm 82 can be rotated readily and the shaft 79 caused to revolve so as to raise or lower the arm 80.

Pivotally connected to the front ends of the arms 80 are hangers 85 each of which has a depending finger 86 at its lower end. This finger is adapted to be inserted into the opening 58 thereunder and a hooked retaining dog 87 is pivotally connected to each hanger and is adapted, when the finger 86 is seated in one of the openings 58, to extend

und the half circle 25 and thus prevent it from withdrawing from the finger 86. A holding ring 88 is slidably mounted on each hanger 85 and is adapted to engage dog 87 so as to hold it against movement relative to finger 86 and thus securely attach the hanger 85 to the half circle 25. It is to be understood that only one of the hangers 85 is placed in engagement with the half circle at one time. If the right end of the scraper blade 24 is back of the left end thereof, the hanger 85 at the right side of the machine is placed in engagement with the half circle. Should the left end of the scraper blade be rearmost, the hanger 85 at the left side of the machine is placed in engagement with the half circle. In either event that end portion of the half circle engaged by the hanger will be elevated when the crank arms 80 are moved upwardly. Thus it will be seen that the rearmost end of the scraper blade 24 can be easily raised so as to tilt the blade longitudinally.

Slidably mounted in the sleeve 48 is the angular rear axle 89 of the machine, the ends of the axle being supported by flanged supporting wheels 90. Axle 89 has rack teeth thereon, as shown at 91 and certain of these teeth are constantly engaged by a gear 92 secured to an upstanding shaft 93 which is journaled in the extension 49 of one of the sleeves 48. A gear 94 is secured to and rotates with the upper portion of shaft 93 and the upper end of said shaft is journaled in a bracket 95 extending from the bottom of the platform 74. A lever 96 is mounted to rotate freely on the shaft 93 and has a lug or tooth 97 adjacent one end and adapted to engage the gear 94. A spring 98 is mounted on the shaft 93 and bears upwardly against lever 96 so as to hold said lever normally in engagement with the gear 94. A handle 99 is provided at the free end of the lever and a bracket 100 is connected to the lower surface of the platform 74 and serves to hold lever 96 against movement under normal conditions. It is to be understood that by disengaging lever 96 from the bracket 100, said lever can be swung in one direction, and, if in engagement with gear 94, will cause shaft 93 to rotate and motion will therefore be transmitted through gear 92 and rack 91 to the axle 89. Said axle will thus be shifted transversely of the machine so as to bring the frame members 45 to any desired position above the axle 89. By swinging lever 96 downwardly against the action of the spring 98, the tooth or lug 97 can be disengaged from gear 94, and said lever thus swung back to its initial position without producing a corresponding movement of the shaft 93. An arch 101 can be mounted on the frame members 45 close to the arched portion 2 of the beam 1 and this arch 101

may support a seat 102 for the driver. Foot rests 103 may also be supported by the respective frame members 45.

As has already been pointed out, the 5 scraper blade 24 can be adjusted angularly in a vertical plane by rotating shaft 79 so as to elevate that end portion of the half circle 25 to which one of the hangers 85 is connected. Thus the blade can be caused to 10 grade an inclined surface. For the purpose of adjusting the blade angularly in a horizontal plane, the pin 59 is disengaged from the half circle 25 and the draw bar 30 is disengaged from the beam 1. The blade 24 15 can then be swung about the ball 22 as a pivot until it has been brought to a desired angle after which pin 59 is reinserted into the half circle and the bar 30 is readjusted into engagement with beam 1 and with the 20 socket 27 adjacent the front end of the scraping blade. The entire blade can be quickly elevated by means of the rack bar 64 and gear 67, as hereinbefore described. As the beam 1 is arched directly in front 25 of the scraper blade, it will be seen that there is no danger of dirt and sod becoming lodged under the beam and interfering with the proper operation of the scraper.

What is claimed is:—

30 1. A road scraper including a beam, said beam having a series of apertures along each side thereof, a scraper blade extending under the beam, said blade being movably connected to the beam, a draw bar, stems extending laterally from one end thereof, one stem being provided for, and adapted to be seated in any one of the apertures of each series, and means upon the bar for engaging the back face of the scraping blade adjacent either end.

2. A road scraper including a longitudinally channeled beam having a series of apertures in each side thereof, a scraping blade extending under and movably connected to the beam, said blade being shiftable angularly in a horizontal plane, a draw bar, oppositely extending stems at one end of the bar one stem being provided for, and insertible into an opening of each series, said 45 bar being curved downwardly and rearwardly so as to extend over the blade, and means upon the back face of the blade and adjacent each end, either of said means being adapted to be engaged by the draw bar.

55 3. In a road scraper the combination with a longitudinally channeled beam having a series of apertures in each side thereof, of a scraper blade extending under and movably connected to the beam, a draw bar having oppositely extending stems at one end one stem being provided for, and insertible into any one of the openings in each series,

said bar being extended rearwardly and downwardly to engage the rear face of the scraper blade, and means carried by the bar 5 for engaging said blade.

4. In a road scraper the combination with a beam and a scraper blade movably connected thereto, of a bracket secured to the lower face of the beam and having a tongue 70 provided with a longitudinal ridge, an arcuate brace upon the rear face of the blade and slidably mounted on the ridge, and means extending through the ridge for holding said arcuate brace against longitudinal 75 movement upon the ridge.

5. A road scraper including a beam, a scraper blade extending thereunder and adjustable angularly in a horizontal plane and also adjustable angularly in a vertical plane, 80 a bracket secured to and arranged under the beam, said bracket having a tongue provided with a longitudinal ridge, an arcuate brace secured to the blade and mounted to slide and rock upon the ridge, and means extending through the tongue, beam and brace for holding said brace against movement longitudinally. 85

6. A road scraper including a beam, a scraper blade connected thereto for universal movement, frame members pivotally connected to the beam and extending rearwardly therefrom, a wheel supported axle carrying the rear ends of said members, a shaft mounted for rotation on the frame 90 members, crank arms extending therefrom, means for rotating the shaft, hangers depending from the crank arms, an arcuate brace upon the scraper, and means for detachably securing the hangers to the brace. 100

7. In a road scraper the combination with a beam and means for supporting the front end thereof, of a wheel supported rear axle, frame members extending from the axle and along the sides of the beam, said members 105 being pivotally connected to the beam adjacent the front end thereof, a guide interposed between and fixedly connected to the frame members, means carried by the frame members for yieldingly supporting the rear end of the beam in the guide, a scraper blade connected to the beam, and means for adjusting the rear end of the beam vertically within the guide to raise and lower the blade. 110

In testimony that we claim the foregoing as our own, we have hereto affixed our signatures in the presence of two witnesses.
